UNITED STATES PATENT OFFICE.

FRANK L. CUPP, OF CHICAGO, ILLINOIS.

FAN.

Application filed August 15, 1921. Serial No. 492,325.

To all whom it may concern:

Be it known that I, FRANK L. CUPP, a citizen of the United States, residing at Chicago, in the county of Cook and State of Illinois, have invented certain new and useful Improvements in a Fan, of which the following is a specification.

This invention relates to a fan of the oscillating type operated by a spring motor directly or in combination with an air pump and a rotating device in connection with the fan shaft. The principal object of the invention is to provide a new and improved fan construction which may be operated by means of a spring motor and to utilize stored up energy of a spring through the intermediary of a pneumatic device for rotating the fan. A further object of the invention is to provide a new and improved rotating device which may be used in connection with a fan or any other device which it is desired to rotate. Other objects will appear hereinafter.

In the accompanying drawings, Fig. 1 is a section elevation of a fan constructed in accordance with the principles of this invention; Fig. 2 illustrates a modified form; and Fig. 3 shows a detail of the rotating device.

A fan having a plurality of blades 4 is secured to the end of a shaft 5 and has a protecting guard 6 composed of wires or the like secured to the fan shaft or to the casing 7 in which the fan shaft is mounted. If the fan is of the oscillating type an elongated opening 8 is provided in the casing to permit such movement of the fan. A bearing 9 supports the shaft 5 and is mounted for free rotation about a vertical axis by means of a hanger 10.

Between the fan and the bearing 9 is a conical housing 11 which is secured against rotation with the shaft 5, as by attaching it to the bearing 9. Within this housing and secured to the shaft is a spiral corrugated or fluted member 12 which fits the housing closely and provides vanes in a passage which diminishes in diameter from the inner to the outer end of the housing 11. At the inner end is an air or fluid inlet 13, and at the outer or reduced end of the housing is a discharge opening 14 through which the air or fluid may escape. The spiral member 12 may be formed of thin sheet metal or any other light material which will maintain a

permanent fluted form, and the inlet 13 is inclined, as shown in Fig. 3, so that the incoming air will directly impinge the vanes of the fluted member and will impart the maximum rotative effort to the shaft 5 and the fan.

In order to supply air under pressure for rotating the fan, a spring 15 which is wound by means of a key 16, has a train of gears 17, the last of which is mounted upon a shaft 18 carrying a disc 19. This disc has a cam or crank arm 20 pivoted to a piston 21 and reciprocated in a cylinder 22 by the rotation of the disc to force air therefrom by means of a pipe 23, the end of which is connected by a flexible hose 24 with the inlet 13. A check valve 25 may be provided at any point in the pipe line to prevent that pressure.

To oscillate the fan the bearing 9 may be provided with depending projections 26 and 27 on opposite sides of the center of the hanger 10 in position to be engaged by corresponding projections 28 and 29 on opposite sides of the disc 19. The rotation of the disc will cause the projections on one side to engage, moving the fan in one direction, and the continued rotation of the disc will engage the projections on the other side thereof to move the fan in the opposite direction. Any other suitable mechanism for oscillating the fan may be employed.

Instead of driving the fan by means of fluid under pressure, a spring motor 30 may be directly engaged to a fan 31 through a train of reducing gears 32.

In operation the fan motor is wound up by hand and the unwinding of the spring furnishes the power to rotate the disc 19 and operate the piston 21 in the cylinder which furnishes air under pressure through the fluted device 12 in the housing 11, imparting rotation to the fan in an efficient manner. The rotation of the disc 19 oscillates the fan transversely in the slot 8 and the flexible hose 24 permits the oscillating movement of the housing 11 without resistance. It is obvious that a fan of this type may be operated for a considerable length of time depending upon the power of the spring motor and the amount of energy that can be stored therein. The fan may be operated by air or fluid under pressure supplied from any source and applied to the device 12, and if desired, cooled air may be employed which

is driven out or scattered by the fan after it escapes from the opening 14 of the device 12.

I claim:

5. In combination, a spring motor, a fan, and pneumatic means operated by the motor for imparting rotation to the fan.
10. A fan in combination with a spring motor and a disc operated by the motor, of pneumatic means comprising a pump having an operating connection with the disc and a vaned device actuated by the pump and attached to the fan for rotating it.
15. A fan mounted at one end of a shaft, means for mounting the shaft to rotate and to oscillate about the other end, pneumatic means including a pump and a device mounted on the fan shaft for rotating it, and means for oscillating the fan shaft.
20. A fan mounted at the end of a shaft, means for mounting the shaft to rotate and to swing transversely, pneumatic means including a pump, and a device mounted on the fan shaft for rotating it, and motive means including a rotatable disc for oscillating the fan shaft and for operating the pump to energize the pneumatic means.

5. The combination with a fan, of a shaft on which it is mounted, an oscillating bearing in which the shaft rotates, a housing attached to the bearing and diminishing in size toward the fan with a peripheral opening at each end thereof, a fluted pneumatic device fitting within the housing attached to the shaft and forming a vaned spiral path 35 from the inlet to the outlet openings, and means to oscillate the bearing, and air pressure means for rotating the device.

6. In a fan, the combination with blades attached to a shaft, of a bearing to support the shaft for rotation and transverse oscillation, a pneumatic device comprising a non-rotatable housing of conical form, and a spiral vaned device within the housing secured to the shaft, means for admitting air 40 under pressure, a spring motor, a disc rotated by the spring roller, a crank connection with the disc for operating the pump, and projections on opposite sides of the longitudinal center of the bearing and on opposite sides of the disc for corresponding engagement to produce oscillation of the bearing when the disc is rotated.

FRANK L. CUPP.
